UNITED STATES PATENT OFFICE.

JAMES PARK, OF TROY, NEW YORK, ASSIGNOR TO THEODORE E. HASLEHURST,
OF SAME PLACE.

WATER HEATER AND FEEDER.

SPECIFICATION forming part of Letters Patent No. 289,930, dated December 11, 1883.
Application filed April 11, 1883. (No model.)

To all whom it may concern:

Be it known that I, JAMES PARK, of Troy, in the county of Rensselaer and State of New York, have invented certain new and useful 5 Improvements in Water Heaters and Feeders, of which the following is a specification.

My invention relates to improvements on the class of heaters and feeders wherein the water is heated and fed into a boiler, or other 10 vessel or apparatus, by means of a current of live steam; and the object of my improvements is to provide the apparatus with a steam-valve that will automatically open and close by the opening and closing of the water-supply valve, 15 as hereinafter described. This object I attain by means of the mechanism illustrated in the accompanying drawing, which forms part of this specification, and which contains a longitudinal section of my apparatus, with a portion 20 of the pipes and fittings shown in side elevation.

As shown in the drawing, A is the outer cylinder or shell of the heater.

B is the inner cylinder for containing steam. 25 Said inner cylinder is secured to the head a of the shell, and is smaller and shorter than the shell A; a water-space, C, is thus formed between the cylinders A and B and the heads a' and b.

30 D is an inlet water-pipe connected to the water-supply and communicating with the water-spaces C. Said inlet-pipe is provided with a T-branch, d', having a stuffing-box, d'', interposed between the stop-cock d and water-supply.

E is a steam supply-pipe communicating with the cylinder B, and provided with an automatic stop-cock, which consists of a valve-casing, E', (like the ordinary globe-valve,) 40 containing a simple puppet-valve, e, whose stem e passes through a stuffing-box on the valve-casing, and is connected to a plunger, d'', whose area, where it is exposed to the pressure of the water, should exceed the area 45 of the valve e sufficiently to overcome any excess in the pressure of the steam over the pressure of the water. Said plunger is adapted to slide in the stuffing-box d'' of the branch d'

of the inlet water-pipe. The stuffing-box d'' should be fixed centrally over the stuffing-box 50 on the valve-casing E, so that the plunger d'' and stem e will range in line with each other.

F is a taper nozzle fixed in the head b of the cylinder B and extending centrally into the inner end of the outlet water-pipe G, so 55 as to leave an annular opening between the said nozzle and outlet-pipe.

The operation of my invention is as follows: On opening the stop-cock d to let a stream of water pass through the pipe D into the water-space C of the heater the current of water 60 passing through said pipe will pass over the opening of the branch d' in a line at right angles to the axis of said opening, and, following a well-known law of fluid pressures, the 65 current will produce a reduction of the pressure (in said branch) acting against the inner end of the plunger d''; and, immediately on this reduction of the pressure, the steam, acting 70 against the under side of the valve e, will force the latter upward, and thus permit a current 75 of steam to pass into the chamber in cylinder B, wherein a portion of the steam will be utilized for heating the water in the water-space C, and then the current of steam, passing out 80 of the cylinder B through the nozzle F, will force the water that is drawn from the water-space C out through the pipe G to the place where it is required. On closing the stop-cock d the accumulation of pressure in the 85 pipe D, due to the impetus of the current of water, will force down the plunger d'' to close the valve e and shut off the inflow of steam.

I claim as my invention—

In a water heater and feeder, the combination, with a water-inlet pipe, D, provided with a stop-cock, d, and branch d', as herein described, of the steam-supply pipe E, provided with a stop-valve, e, connected to the plunger d'', and adapted to be operated by the pressure 90 of water in the pipe D, as and for the purpose herein specified.

JAS. PARK.
